UNITED STATES PATENT OFFICE

169,643

BOX COVER

Franz Wagner, Chicago, Ill., assignor to Ekco
 Products Company, Chicago, Ill., a corporation of Illinois

Application November 17, 1951, Serial No. 17,456

Term of patent 7 years

(Cl. D58—12.6)

To all whom it may concern:

Be it known that I, Franz Wagner, a citizen of the United States, residing at Chicago, county of Cook, State of Illinois, have invented a new, original, and ornamental Design for a Box Cover, of which the following is a specification, reference being had to the accompanying drawings forming part thereof.

Fig. 1 is a top plan view of a box cover embodying my new design.

Fig. 2 is a side elevation of the box cover as viewed from the left side.

Fig. 3 is a side elevation thereof as viewed from the right side.

Fig. 4 is an end elevation thereof as viewed from either end.

I claim:

The ornamental design for a box cover, as shown.

FRANZ WAGNER.
